UNITED STATES PATENT OFFICE.

FREDERICK GALBRAITH, OF QUEENS, AND WILLIAM VALET, OF NEW YORK, N. Y.

WRAPPER FOR TEXTILE PIECE GOODS.

Application filed June 10, 1925. Serial No. 36,148.

This invention is a wrapper for a bolt of piece goods.

The purpose of the invention is to provide a wrapper for protecting the piece goods from dust and dirt during storage, shipping and handling, which may be economically manufactured, which may be readily opened for obtaining access to the goods in the wrapper, and readily closed for doing up the goods again before putting them back on the shelf.

The wrapper of this invention comprises a body portion and side and end flaps. Opposite pairs of flaps are secured to each other by means formed as part of the flaps themselves, thereby dispensing with tying tapes or other forms of fastening devices that need to be clamped on or pasted to the wrapper. Since these wrappers are usually 20 of paper, such pasted on or clamped on devices are apt to be torn loose from the paper, a disadvantage overcome by this invention.

According to this invention, opposite pairs of flaps are secured to each other by tongues 25 formed in one of the flaps and by cooperating slots formed in the opposite flap. More specifically, two slots are provided for each tongue; the tongue is threaded into the first slot, then out of the second slot, and 30 is then bent backwardly and tucked into the first slot. The two opposite flaps are thus securely locked together, the end of the tongue is concealed, and the top of the wrapper is substantially flat, so that one package 35 of goods can be slid into place on the shelf on top of another piece of goods.

The preferred embodiment of the invention is illustrated in the accompanying drawings wherein:

40 Fig. 1 is a perspective view of the wrapper in use;

Fig. 2 is a section on the line 2—2 of Fig. 1;

Fig. 3 is a section on the line 3—3 of Fig. 1;

Fig. 4 is a plan view of the blank from which the wrapper is formed.

Fig. 5 is a section on a line 5—5 of Fig. 1; and

50 Fig. 6 is an enlargement of the interlocking means shown near the left of Fig. 2.

Referring now to these drawings, in which similar reference characters indicate similar parts, the wrapper comprises a body portion 1, side flaps 2 and 3, and end flaps 4

and 5. The dotted lines 6 indicate lines of fold.

One of the side flaps, such as 2, and one of the end flaps such as 5 is provided with one or more tongues 7 and 7', respectively, 60 preferably formed integrally with the respective flap.

The side flap 3 opposite flap 2 is provided with a pair of parallel slots 8 and 9, defining between them a bridge member 10. 65 The end flap 4 opposite flap 5 is provided with a pair of parallel slots 8' and 9' defining between them a bridge member 10'. The dotted lines 11 on the tongues indicate lines of fold. 70

In use, the bolt of goods, which is substantially the same size as the body portion 1, is placed on the body portion 1, and the end flaps 4 and 5 folded inwardly on the lines 6, 6. The tongue 7' on the flap 5 is then threaded into the nearer slot, which is the slot 9', is passed under the bridge member 10' (see Fig. 6), is then threaded out through the slot 8', is then bent backwardly over the bridge member 10', is then threaded into 80 the slot 9' again, and the end of the tongue 7' indicated at 7", tucked in under the bridge member 10', whereby it is concealed and securely held. 75

After the two end flaps are thus locked 85 together the side flaps 2 and 3 are folded inwardly toward each other on the lines 6, 6, and the tongues 7 preferably three in number, interlocked with respective pairs of slots 8 and 9 in the same manner as has been described in connection with the end flaps. 90 More specifically, and as shown in Fig. 5, the tongue 7 is threaded into slot 9, is then passed under the bridge member 10, out of slot 8, then bent backwardly over the bridge 95 member 10 and its end tucked in under the bridge member 10, thereby locking the two side flaps together and concealing and protecting the end of the tongue.

The wrapper is preferably made of paper. 100 The showing in Figs. 3, 5 and 6 of the interlock between the tongue and the slots, is necessarily exaggerated, in order to bring out the details. In practice, the finished package is substantially flat on top, the interlock comprising only several thicknesses of paper. The use of strings, tapes or other tying means is entirely eliminated. 105

The slots and tongue are preferably reinforced for preventing tearing. The reen- 110

forcement for the slots 8' and 9' is shown as a piece of paper or fabric 12' pasted on the flap 4, directly over the slots 8' and 9', the reenforcing piece 12' of course having slots cut in it which register with the slots 8' and 9'. The slots 8 and 9 are similarly reinforced with reenforcing pieces 12 pasted onto the flap 3. The tongue 7' is reenforced with a pasted-on reenforcing strip 13', and the tongues 7 similarly reenforced with pasted on reenforcing pieces 13.

While we have illustrated our invention in some detail, it should be understood that the invention is not to be limited to the exact details here shown, but may be carried out in other ways, as defined within the scope of the appended claims.

We claim as our invention:

1. In a wrapper for piece goods, the combination of a body portion having two cooperating side flaps and two cooperating end flaps, one pair of flaps folding over the other pair of flaps, a tongue carried by one flap of each pair of flaps and two slots formed in the cooperating flap, the two slots defining a bridge member between them, the tongue being threaded through the slots in succession then bent back over the bridge member, threaded again into the first slot, and bent over the other edge of the bridge member and tucked underneath it, whereby the tongue is locked to both edges of the bridge member.

2. A wrapper for a bolt of piece goods

comprising a body portion and two oppositely disposed flaps carried thereby, the flaps being foldable into overlapping relationship, the lines of fold of the flaps being substantially parallel and extending longitudinally of the body portion, one of the flaps carrying a tongue and the other carrying a pair of slots defining a bridge member between them, the tongue being threaded through the slots in succession and then bent back over the bridge member and threaded into the first slot, for locking the tongue to the bridge member.

3. A wrapper for a bolt of piece goods comprising a body portion and two oppositely disposed flaps carried thereby, the flaps being foldable into overlapping relationship, the lines of fold of the flaps being substantially parallel and extending longitudinally of the body portion, for substantially its full length, the flaps carrying interengaging locking means, comprising a tongue carried by one flap and a pair of cooperating slots carried by the other flap, the tongue being threaded through the slots in succession and then bent back and threaded into the first slot, whereby the tongue is locked and its end concealed, and means for preventing tearing.

In testimony whereof we affix our signatures.

FREDERICK GALBRAITH.
WILLIAM VALET.
